UNITED STATES PATENT OFFICE.

HENRY W. YOUNGQUIST, OF MANCHESTER, NEW HAMPSHIRE.

BRAKE MECHANISM FOR TALKING MACHINES.

Application filed September 28, 1921. Serial No. 503,774.

To all whom it may concern:

Be it known that I, HENRY W. YOUNGQUIST, a citizen of the United States, and resident of Manchester, county of Hillsborough, State of New Hampshire, have invented an Improvement in Brake Mechanism for Talking Machines, of which the following description, in connection with the accompanying drawing, is a specification, like characters on the drawing representing like parts.

This invention relates to improvements in starting and stopping mechanisms for talking machines and the general object thereof is to provide a novel and relatively simple braking means which can be applied to usual types of talking machines.

A further object of the invention is to provide a novel braking means adapted to co-operate with the braking means of the usual centrifugal governor of a machine of the class described in such a manner as to stop the rotation of the record carrying means at the conclusion of the record.

More particularly the object of the invention is to provide a novel stop mechanism operable by the movement of the tone arm across a predetermined field at the conclusion of the reproduction to arrest the rotation of the record supporting means.

The invention further contemplates the provision of a braking means operable by the movement of the tone arm in the opposite direction from that above described, through a predetermined field outside of the field of reproduction of the record, to prevent rotation of the record supporting means.

By reason of the combination of these braking mechanisms means are provided for retaining the record supporting means against rotation until the reproducing means, carried by the tone arm, is moved toward reproducing position whereupon the record supporting means will be released and continue to rotate until the reproducing means traverses a predetermined field at the end of the reproduction and causes the other braking means to stop the machine.

Preferably the construction is such that the beginning of the movement of the tone arm in a direction to cause the actuation of one of the braking mechanisms will cause the release of the other braking mechanism.

These and other objects and features of the invention will more fully appear from the following description and the accom-

panying drawings and will be pointed out in the claims.

A preferred embodiment of my invention is illustrated herein as applied to a usual type of talking machine provided with rotatable means for carrying a disk record, but it will be understood that the invention is applicable also to machines having rotatable means for carrying a cylindrical record and that the invention may be employed in connection with other mechanisms than talking machines to which it may be applicable.

In the drawings:

Fig. 1 is a plan view of a sufficient portion of a talking machine to illustrate the application of my invention thereto, portions of the frame, the record supporting disk and the record being broken away to illustrate the governor mechanism and a preferred means for applying the brake thereto;

Fig. 2 is a detail vertical sectional view on an enlarged scale, on line 2-2 Fig. 1, illustrating the governor, and a portion of the braking mechanism in elevation.

The talking machine illustrated herein is of a usual type comprising a base 1 which carries the usual spring motor, (not shown), which serves to actuate a driving shaft 2 having at its upper end suitable means engaging a felt covered record supporting disk 3. The usual type of record 4 is placed upon the record supporting disk 3 and the spiral grooves 5 of the record are engaged by the usual needle which forms a part of the sound-reproducing means or sound box 6 which is carried at the end of a tone arm 7 which is pivotally mounted in a suitable stand 8 on said base.

In the construction illustrated the speed of rotation of the record supporting disk 3 is controlled by a governor which is actuated from the main shaft 2. As shown herein a worm gear 9 which is fixedly secured to the driving shaft 2 engages a worm 10 upon a governor shaft 11 which is mounted in suitable bearings in brackets 12 and 13. A collar 14, fixedly secured to the governor shaft 11, is connected by leaf springs 15 to a sleeve 16 which is slidably movable axially upon the governor shaft. Weights 17, which are connected to the respective springs 15 intermediate of their length, are thrown out by centrifugal force of rotation in such a manner as to move the sleeve 16 axially on said shaft to cause a flexure of the springs there-

by shortening their effective length and moving the sleeve 16 toward the plane in which the weights rotate. A rotatable braking member, preferably in the form of a 5 disk 18, is fixedly secured to the sleeve 16 so that it moves with said sleeve. The speed of rotation of the governor shaft is controlled by a brake 19 which is positioned to engage the rotating braking member 18 10 when the latter has been moved a predetermined distance and by the braking action upon said disk acts to retard the movement of the governor shaft and consequently the main shaft to a predetermined speed. Suitable 15 means, (not shown), are provided for adjusting the brake 19 in order that any desired speed of revolution may be maintained. The governor mechanism thus described is well known and except for very slight 20 variations is common to both the disk and cylindrical type of talking machine.

The present invention contemplates the provision of braking mechanism operable by the movement of the tone arm through a predetermined field at the end of the reproducing portion of the record to arrest the rotation of the governor and consequently to stop the machine. In the preferred embodiment of the invention illustrated herein this is accomplished 25 by providing a reciprocably mounted brake member 20 having a brake shoe 21 adapted, when the reciprocating member 20 is moved longitudinally, to engage the rotary brake member 18 of the governor. The brake member 20 desirably is slidably mounted in a suitable guide or guides 22 and is provided with an offset end 23 which is yieldably connected by a helical spring 24, or other suitable means, to the 30 end of an actuating lever 25 which is pivotally mounted upon a stud 26 carried by the base 1, the reciprocating member 23 desirably being provided with an extended slot 27 through which the end of the lever 25 extends. 35

The opposite arm of the lever, for convenience in construction, is provided with an offset 28 which is pivotally connected by a stud 29 to one end of a link 30, the opposite 40 end of which is pivotally mounted upon a stud 31 in the end of an arm 32 which is rigidly connected by screws 33, or other suitable fastenings, to the tone arm or a member which is rotatable therewith.

The reciprocating member, the lever 25, link 30, and arm 32 are so proportioned that the brake shoe 21 of the reciprocating brake member 20 will not be brought into engagement with the rotating brake member 18 of the governor until the needle of the sound-reproducing member 6 has passed beyond the reproducing portion of the record; but while the tone arm is traversing the final convolutions of the record the brake shoe 21 will be gradually applied to the rotatable disk 18

of the governor. As the speed of rotation of the disk 18 is decreased the governor springs gradually straighten and thus progressively increases the braking force of the brake 21 until the machine is stopped. During this 70 action the spring 24 yields to the movement of the disk 18.

In order to effect a relatively rapid stoppage of the machine the groove of the record may if desired terminate in a series of more 75 rapidly converging convolutions 34 than those forming the reproducing portion of the disk. Where such supplemental convolutions are employed no means are required for adjusting the position of the reciprocating 80 brake member. However, it will be understood that any suitable means for adjusting the brake member may be used, such, for example, as by forming the link 30 in adjustable sections coupled by a bolt and slot connection 35 and 36, or other suitable well known means.

The present invention contemplates the combination with the braking mechanism for arresting rotation of the record supporting 90 member of means for preventing the rotation of the record supporting member when the machine is not in use, operable by the movement of the tone arm in the opposite direction to that for applying the brake at the 95 conclusion of the reproduction of the record, so that the initial movement of the tone arm when in one braking position towards the position in which the other brake will be applied will instantly release the applied 100 brake. The mechanism, therefore, comprises automatic starting and stopping mechanism operable by the movement of the tone arm.

The mechanism for arresting the rotation of the record supporting member, when the 105 tone arm is moved from operative position, comprises a brake shoe 37 which is illustrated herein as applied to the rim of the record supporting disk 3 and is carried at the end of one arm 38 of a lever which is pivotally 110 mounted upon a stud 39 upon the base. The other arm 40 of the lever extends beyond the pivot and is actuated through a spring 41 which is engaged by an arm 42 also pivotally mounted upon a stud 39 and adapted to 115 be engaged by a stud 43 upon the arm 32 which is connected to the tone arm. Thus when the tone arm is swung to inoperative position, as illustrated in full lines in Fig. 1, the stud 43 moves the arm 42 outwardly compressing the spring 41 and causing the same to move the lever 40 about its pivot 39 and apply the brake 37 to the record supporting means. When the tone arm is moved in the other direction the stud 43 is removed from 120 engagement with the arm 42 thereby releasing the pressure upon the lever 40. The brake is then withdrawn from engagement with the record supporting means by a helical spring 44 which is connected at one end 125

to the arm 38 of the lever and at its other end to a bracket 45 carried by the base 1. A stud 46 may be provided to limit the movement of the lever arm 38 caused by the action of the 5 spring 44.

It will be remembered that the arm 32 is connected to the link 30 and causes the actuation of the governor braking mechanism when the tone arm is swung to the dotted 10 line position illustrated in Fig. 1 at the conclusion of the reproduction of the record.

The interposition of the spring 41 between the arm 42 and the lever arm 40 which it actuates provides sufficient resilience to prevent bending or injury to the brake lever 40 if the tone arm is swung by the operator 15 too vigorously into inoperative position, and also serves to yieldingly apply the brake so that the rotation of the record supporting 20 means will not be arrested so quickly as to injure its actuating mechanism.

When the machine is at rest the tone arm will normally be held in the full line position illustrated in Fig. 1 with the brake 37 25 applied to the record supporting means. In operating the machine the record is placed upon the record supporting member in the usual manner. The tone arm is then swung about its pivot to bring the sound box which 30 carries the needle over the outer convolution of the spiral groove of the record and the needle placed in said groove. This movement of the tone arm withdraws the stud 43 from its engagement with the lever. The 35 spring 44 thereupon releases the brake from engagement with the rotatable record supporting means and permits the automatic starting of the machine. As the needle of the sound box traverses the spiral groove 40 of the record the tone arm is swung about its pivot and the governor brake is gradually moved toward braking position. After the reproduction of the record is completed the continued movement of the tone arm, either 45 in the usual final convolutions of the spiral or in the special convolutions 34 illustrated herein, eventually forces the brake shoe 21 into engagement with the rotatable brake disk of the governor thereby arresting the 50 machine and retaining the same in arrested position. When the record is to be removed and replaced the sound box is raised in the usual manner and moved toward the inoperative position illustrated in full lines in 55 Fig. 1. As soon as it is raised from the terminal convolutions of the record and moved toward inoperative position the governor brake is released and when the tone arm has been completely swung to inoperative 60 position the brake 37 is applied. This movement of the tone arm usually is accomplished with sufficient rapidity to cause the application of the brake 37 before the driving mechanism has started the rotation of 65 the record supporting means, or at least be-

fore the record supporting means has acquired any considerable momentum, so that very little force is necessary to arrest its rotation.

It will be understood that the embodiment 70 of the invention disclosed herein is illustrative and not restrictive and that various modifications in design, construction and arrangement of parts, to adapt the same to different types of talking machines, may be 75 made within the spirit and scope of the following claims. It will also be understood that while the invention is herein described as applied particularly to talking machines it may be used in connection with other 80 analogous machines and devices.

Having thus described my invention, what I claim as new, and desire to secure by Letters Patent, is:

1. In a talking machine comprising rotatable means for supporting a spirally grooved record, means for actuating the same, a governor having braking mechanism for controlling the speed of rotation of said record supporting means and a tone arm 85 having sound-reproducing means adapted to engage and be progressively moved by the spiral groove of said record; braking means yieldably connected to said tone arm movable by the traverse of said tone arm 90 across a predetermined field into co-operative relation to said governor braking mechanism and operable thereby to arrest the rotation of said record supporting means. 95

2. In combination with a talking machine 100 comprising rotatable means for supporting a spirally grooved record, a governor having a rotary shaft and centrifugally operated instrumentalities actuated thereby, a rotatable brake member movable axially of said 105 shaft by said centrifugal instrumentalities and a tone arm having sound-reproducing means adapted to engage and be moved progressively by the spiral groove of the record; stop mechanism comprising a brake connected to said tone arm and movable gradually by the traverse of the tone arm produced by the final convolutions of the groove of the record into engagement with the rotatable 110 brake member of said governor. 115

3. In combination with a talking machine comprising rotatable means for supporting a spirally grooved record, a governor having a rotary shaft and centrifugally operated instrumentalities actuated thereby, a rotatable 120 brake member movable axially of said shaft by said centrifugal instrumentalities and a tone arm having sound-reproducing means adapted to engage and be moved progressively by the spiral groove of the record; 125 stop mechanism comprising a brake connected to said tone arm and movable gradually by the traverse of the tone arm produced by the final convolutions of the groove of the record into engagement with the rotatable 130

brake member of said governor in opposition to the direction of axial movement of said rotatable brake member caused by the diminution of the rotation of said centrifugally operated instrumentalities.

4. In combination with a talking machine comprising rotatable means for supporting a spirally grooved record, a governor having a rotary shaft and centrifugally operated instrumentalities actuated thereby, a rotatable brake member movable axially of said shaft by said centrifugal instrumentalities and a tone arm having sound-reproducing means adapted to engage and be moved progressively by the spiral groove of the record; stop mechanism comprising a reciprocably mounted brake member adapted to co-operate with the rotary brake member of said governor, a lever yieldably connected to said reciprocable brake member and a link connected to said tone arm and operable by the movement of said tone arm through a predetermined field to cause the application of said reciprocable brake member to said rotatable brake member.

5. In combination with a talking machine comprising rotatable means for supporting a spirally grooved record, a governor having a rotary shaft and centrifugally operated instrumentalities actuated thereby, a rotatable brake member movable axially of said shaft by said centrifugal instrumentalities and a tone arm produced by the final convolutions of the groove of the record into engagement with the rotatable brake member of said governor and yieldable means intermediate of the tone arm and the brake which is actuated thereby.

6. In combination with a talking machine comprising rotatable means for supporting a spirally grooved record, a governor having a rotary shaft and centrifugally operated instrumentalities actuated thereby, a rotatable brake member movable axially of said shaft by said centrifugal instrumentalities and a tone arm having sound-reproducing means adapted to engage and be moved progressively by the spiral groove of the record; stop mechanism comprising a reciprocably mounted brake member adapted to co-operate with the rotary brake member of said governor and means yieldably connected to said reciprocable brake member operable by the movement of said tone arm through a predetermined field to cause the gradual application of said brake to said rotatable brake member.

7. In combination with a talking machine comprising rotatable means for supporting a spirally grooved record, a governor having a rotary shaft and centrifugally operated instrumentalities actuated thereby, a rotatable

brake member movable axially of said shaft by said centrifugal instrumentalities and a tone arm having sound-reproducing means adapted to engage and be moved progressively by the spiral groove of the record; stop mechanism comprising a reciprocably mounted brake member adapted to co-operate with the rotary brake member of said governor, a lever yieldably connected to said reciprocable brake member and a link connected to said tone arm and operable by the movement of said tone arm through a predetermined field to cause the application of said reciprocable brake member to said rotatable brake member.

7. In a talking machine comprising rotatable means for supporting a spirally grooved record, a tone arm having sound-reproducing means adapted to engage and be moved by the spiral groove of the record; starting and stopping mechanism comprising a plurality of braking means operable by movements of the tone arm across an initial and a terminal field in different directions to arrest said record supporting means, the initial movement of the tone arm to record-engaging position acting to release one braking mechanism and the final movement of the tone arm in the same direction serving to actuate the other braking mechanism.

8. In a talking machine comprising rotatable means for supporting a spirally grooved record, a tone arm having sound-reproducing means adapted to engage and be moved by the spiral groove of the record; starting and stopping mechanism comprising a plurality of braking means operable by movements of the tone arm across an initial and a terminal field in different directions to arrest said record supporting means, the connections to said tone arm being such that the movement of the tone arm in a direction to actuate one of said braking means will cause the release of the other braking means.

In testimony whereof, I have signed my name to this specification.

HENRY W. YOUNGQUIST.
